UNITED STATES PATENT OFFICE.

DAVID SENIOR AND HOBSON FITTON, OF MADISON, INDIANA.

CARDING-MACHINE.

SPECIFICATION forming part of Letters Patent No. 372,771, dated November 8, 1887.

Application filed October 8, 1886. Serial No. 215,685. (No model.)

To all whom it may concern:

Be it known that we, DAVID SENIOR and HOBSON FITTON, both citizens of the United States, and residents of Madison, in the county 5 of Jefferson and State of Indiana, have invented certain new and useful Improvements in Carding-Machines, of which the following is a specification.

Our invention relates to improvements in 10 machines for carding fibers—notably wool and cotton—being applicable to both breaker and finisher cards; and the object of our invention is in part to provide means for keeping the wire teeth of the doffers always clean and 15 sharp, whereby the machine is enabled to produce uniformly good work from coarse or inferior stock and yield better results as to quantity, and in part to provide means for preventing the bottom doffer of the finisher-card from 20 catching the long coarse fiber pendent from the sliver or roving above, and thus breaking it down, and for pressing and smoothing the sliver on the doffer.

Our invention consists, in part, in providing 25 a carding-machine with a toothed stripper-roller set above the doffer and its teeth arranged to pass between the wire teeth of the doffer and to rub against the same, said teeth being bent so as to incline forward or in the 30 direction of the rotation of said roller, and said roller being set quite close to the main carding-cylinder, but out of contact with same, or so that their respective teeth do not intersect.

Our invention also consists, in part, in providing 35 a finisher-card with a smooth roller arranged under the top doffer and close to the main cylinder, which roller prevents the bottom doffer from catching fibers pendent from 40 the sliver on the upper doffer and breaking it down. This roller also smooths and presses the fiber on the doffer close and straight, and thus aids in producing an even and smooth sliver.

In the drawings, which serve to illustrate 45 our invention, Figure 1 is an outline diagram of a finisher-card, showing the position of the parts embodying our invention as applied thereto. Fig. 2 is a similar view of a 50 breaker-card, showing the position therein of

the part embodying our invention. Fig. 3 is a view, on a larger scale, of a part of a finisher-card provided with our improvements.

Referring first to Figs. 1 and 3, wherein our improvements are shown applied to a finisher-card with top and bottom doffers of the ordinary construction, A represents the main cylinder; B, the fancy or "raiser;" C, the top doffer, and C' the bottom doffer, each doffer making a separate roving or sliver. These, 55 as well as the other parts of the finisher seen in Fig. 1, but not referred to, may be constructed and driven in the usual way.

It is well known by those who are accustomed to work carding-machines that the teeth 60 of the doffer quickly become dirty and dull, especially when working coarse or low stock, and require to be frequently cleaned and ground. They will also, when not kept in good working condition, produce an uneven 65 and irregular roving, and consequently an uneven yarn. To obviate this defect, we mount 70 over the top doffer, C, a stripper-roller, D, which has teeth which pass between the wire teeth on the doffer, but do not interlock or engage the same.

We usually cover the roller D with ordinary 75 card-clothing, in order to provide it with teeth; but metal teeth of a similar character of any kind will serve. These teeth are bent so as to 80 incline forward in the direction in which the roller D rotates, as seen in Fig. 3; or, in other words, they are arranged in a manner similar to the teeth on the main cylinder A. These teeth do not intersect the teeth on the main 85 cylinder, but only those on the doffer. The roller D revolves in the same direction as the doffer, and the teeth on said roller pass between the teeth on the doffer and in rubbing-contact therewith, whereby they serve to clean 90 and sharpen the teeth of the doffer and keep the latter in a uniformly good working condition.

We arrange the roller D close to the main cylinder A, as shown, in order that it may 95 transfer the fiber taken from the doffer to the cylinder. The roller D is driven positively, and it may be driven from the doffer-shaft by toothed gearing or by a belt.

In Fig. 3 the dotted circles a a' represent 100

the pitch circles of gear-wheels on the doffer-axis and roller-axis, respectively, and the dotted circle *b* represents the pitch circle of an intermediate gear-wheel. These gears will 5 drive the roller D with a speed about twenty per cent. greater than the speed of the doffer.

The bottom doffer, C', is provided with a stripper-roller, D', which is constructed and operates in precisely the same way as the 10 roller D. Therefore it will need no further description.

Below the top doffer, C, is arranged a smooth roller, E, which we call a "protector" roller or "smoother." This roller is so placed as to 15 be in peripheral contact, or nearly so, with the tips of the teeth on the doffer, and it stands quite close up to the main cylinder. Its function is to prevent the long fibers from the 20 sliver from hanging down and being caught in the teeth of the bottom doffer, C', which would break down the sliver. Said roller also presses upon and smooths and evens the 25 sliver taken off by the top doffer. We have shown the machine provided with but one 30 roller, E, and that arranged under the top doffer; but so far as the pressing and smoothing of the sliver is concerned, a similar roller might be placed under the bottom doffer also with like good results. We prefer to give the 35 roller E a little greater peripheral speed than that of the doffer.

The proportionate sizes of the stripper-rollers D D' and the protector-roller E with respect to the size of the doffer is not very 40 important. We will say, however, that we usually make the stripper-rollers about three inches in diameter and the protector-roller the same, or a little less, according to the room or space in the machine.

Fig. 2 shows the application of our stripper-roller D to a breaker-card. As the construction, arrangement, and operation are precisely the same as that already described with ref-

erence to the finisher-card, no further description of this application of it will be necessary. 45

The roller E may be used to advantage on the breaker-card, as seen in Fig. 2, where it serves to prevent the fiber from flying off the cylinder and smooths down the sliver.

Having thus described our invention, we 50 claim—

1. In a carding-machine, the combination, with the main cylinder and doffer arranged in the usual manner, of a stripper-roller mounted over the doffer and positively driven in the 55 same direction as the doffer, said roller having card-teeth bent or inclined forward in the direction of its rotation, and said teeth intersecting the teeth on the doffer, but not those on the main cylinder, substantially as described.

2. In a finisher-card, the combination, with the main cylinder A and the top and bottom doffers arranged in the usual manner, of a 65 smooth roller, E, arranged under the top doffer and in peripheral proximity thereto and close to the main cylinder A, substantially as and for the purposes set forth.

3. In a finisher-card, the combination, with the top doffer, C, and bottom doffer, C', of 70 the toothed stripper-roller D, with its teeth in rubbing contact with the teeth on the doffer C, the stripper-roller D', with its teeth in rubbing contact with the teeth on the doffer C', and the smooth roller E, arranged under the 75 top doffer and in peripheral proximity thereto, substantially as set forth.

In witness whereof we have hereunto signed our names in the presence of two subscribing witnesses.

DAVID SENIOR.
HOBSON FITTON.
